RUG CUSHION OR SIMILAR ARTICLE

Dixon R. Harwin, Alfred Stern, and Virgil H. Bodle, Los Angeles County, Calif., assignors to National Sponge Cushion Co., Inc., Los Angeles, Calif., a corporation of California

Application December 27, 1952, Serial No. 22,895

Term of patent 14 years

(Cl. D92—21)

To all whom it may concern:

Be it known that we, Dixon R. Harwin, Alfred Stern, and Virgil H. Bodle, citizens of the United States, residing respectively, in the city of Los Angeles, in the city of Los Angeles, and in the city of Temple City, in the county of Los Angeles, and State of California, have invented a new, original, and ornamental Design for Rug Cushion or Similar Article, of which the following is a specification, reference being had to the accompanying drawing, forming part thereof.

Fig. 1 is a plan view of a rug cushion or similar article, showing our new design.

Fig. 2 is an enlarged fragmentary view of the design shown in Fig. 1.

Fig. 3 is a profile view thereof, taken along the lower edge of Fig. 2.

The dominant features of the design reside in the portions shown in full lines.

We claim:

The ornamental design for a rug cushion or similar article, substantially as shown and described.

DIXON R. HARWIN.
ALFRED STERN.
VIRGIL H. BODLE.
